UNITED STATES PATENT OFFICE.

WILLIAM B. THOMAS, OF ATHENS, GEORGIA.

FREIGHT-CHECKING DEVICE.

SPECIFICATION forming part of Letters Patent No. 329,345, dated October 27, 1885.

Application filed March 14, 1885. Serial No. 158,931. (No model.)

To all whom it may concern:

Be it known that I, WILLIAM B. THOMAS, a citizen of the United States, residing at Athens, in the county of Clarke and State of Georgia, 5 have invented a new and useful Improvement in Freight-Checking Devices, of which the following is a description.

In loading cotton-bales in cars mistakes in tallying frequently occur, so that a discrepancy in the accounts of the consignor and consignee result, with consequent loss to one or the other, and trouble and annoyance to both. I propose to avoid this by the use of an automatic check or tally; and to this end I have 15 devised the device or apparatus forming the subject of this application.

The invention consists in the construction and combination of parts hereinafter described and claimed, a tilting lever being the principal feature, and means for connecting it with registering mechanism secondary features. The device is placed on the platform at the station or depot, directly in front of the door 20 of the car to be loaded, and as the truck on 25 which the cotton bale is wheeled into the car passes over it the tilting lever is depressed, and thereby causes the register to make the required record.

In accompanying drawings, Figure 1 is a 30 front side view of a depot or station platform and my invention placed thereon in readiness for operation. Fig. 2 is a front view of the registering mechanism enlarged, a portion of the case being broken away to show the 35 interior construction. Fig. 3 is a vertical section on line zz of Fig. 2. Figs. 4 and 5 are cross-sections on lines xx and yy , respectively, of Fig. 1. Fig. 6 is a perspective view of the invention.

40 The letter A indicates the tilting flange or lever; B, the grooved base-piece in which it is journaled; C, the registering mechanism, and D a depot or station platform. The said lever is a long narrow plate or thin bar, and is rigidly attached to or formed solid with a rock-shaft, E. The latter is journaled in a lengthwise recess or groove, a , formed in the upper side of the base B, which is inclined each way therefrom to facilitate passage of truck-wheels 45 over it. One end of shaft E is bent upward to form a lever-arm, b, which has an eye or

loop for engaging with the hooked end d of a pull-rod, F, that operates the registering mechanism proper. Contiguous to the latter the shaft E is provided with lugs or arms f , 55 on which a spring, g, bears, as shown in Figs. 1 and 4, for the purpose of holding the flange A normally vertical.

It will be noted that recess a in base B has a form that adapts it to receive the flange A 60 when thrown down laterally.

So far as described the operation of the invention is as follows: The device is placed on the platform D, parallel to the side of the car to be loaded, and directly in front of the door 65 of the same. In order to enter the car, each truck loaded with a cotton-bale must pass over the base B, and in doing so the wheels necessarily come in contact with and tilt the flange A laterally, so that it lies down in the 70 recess a , as shown in dotted lines, Fig. 5. This obviously will rotate the rock-shaft E to the right, (see arrow Fig. 3,) so that its lever-arm b pulls down the hook-rod F, and thereby operates the registering mechanism. Thus 75 a unit-record is made each time a truck passes over the flange and base A B. The registering mechanism has two dials or indicators and corresponding indexes or pointers. The lower and smaller dial, g' , indicates units to 80 ten, inclusive, and the larger dial g'' indicates units and tens, preferably tens only. On the shaft h , carrying the pointer of dial g' , are mounted a ratchet-wheel, i, and spur-wheel, j. The latter meshes with the larger toothed 85 wheel k on the shaft l , to which the pointer of the larger dial g'' is affixed. Such larger gear k has one hundred teeth, and the smaller, j , has ten. Hence for one revolution of the small gear the larger is moved but one-tenth of a 90 revolution. The ratchet i has ten teeth, like its neighbor, the small gear j . The hook of pull-rod F engages a tooth of ratchet i when pulled downward, but rides over the next tooth above when it rises to its original position. The ratchet is prevented from backward rotation by a pawl, h' , Figs. 1 and 2. To allow the pull-rod F the lateral movement required to enable it to thus pass over the ratchet-teeth, it is arranged in guides $m m'$, 95 the upper one having a wide slot and a spring for holding the pull-rod normally engaged

with the ratchet, as shown. A spiral spring, *n*, is attached to and encircles the pull-rod *F* between the guides *m m'*, and rests on the lower one. Its function is to push the rod *F* up after each pull. It also supplements the action of the plate-spring *f*, Fig. 4, in holding the tilting flange *A* normally vertical. As before stated, the lower end, *d*, of the pull-rod *F* is hook-shaped, the point of the hook 10 being horizontal, to allow the eye of the lever-arm *b* to readily engage with and disengage from the hook. This it does alternately when a truck passes into and out of a car—that is to say, when the truck passes in, the 15 lever *A* tilts to the right, Figs. 3, and 5, so that the lever-arm *b* pulls down the pull-rod *F* and rotates the ratchet *i* one-tenth of a revolution, whereby the pointer of the smaller dial *g* points to Fig. 1. When the truck 20 passes back over the flange *A*, the latter turns outward, and the lever-arm *b* consequently turns to the left, Fig. 3, and out of contact with the hook *d* of pull-rod *F*. This construction and combination of the pull-rod and 25 lever-arm is therefore important, yet so simple as to have no liability to become inoperative. For every complete revolution of the ratchet *i* the large gear *k* will make one-tenth of a revolution, and its index will then 30 point to the figure 10 on the larger dial *g'*. When the car has been filled, the number of bales it contains may be instantly and correctly ascertained by reading the dials *g' g''* in conjunction. For convenience in moving 35 the tallying device from place to place on the platform *D*, I provide a roller, *o*, at one end and handles *p* at the other, as shown in Figs. 1 and 6. By taking hold of the handles and elevating that end of the device the roller will bear on the platform, so that the device 40 may be easily pushed along to the desired point.

It is obvious the device is adapted for use in registering various other kinds of freight besides cotton-bales.

I do not claim the combination of a registering mechanism and a lever so arranged as to be depressed by a truck passing over it, since I am aware this is not new.

Having thus described my invention, what 50 I claim as new is—

1. The combination, with a registering mechanism, of the long tilting lever or blade *A*, journaled in a horizontal position, but standing normally vertical, and adapted to 55 tilt either way, the base - piece provided with a groove to receive said lever, and also beveled on each side, and a pawl and ratchet connecting the said lever with the registering mechanism proper, substantially as shown 60 and described.

2. The combination, with a registering mechanism and the grooved base-piece, of a tilting lever provided with lateral arms or lugs, the spring *g*, acting on the latter, for 65 holding said lever normally elevated, and means for connecting said lever and registering mechanism, substantially as shown and described.

3. The combination, with registering mech- 70 anism and the pull-rod *F*, having its lower end, *d*, constructed in the hook form specified, of the tilting lever *A*, having the bent end *b*, which is adapted to engage with and disengage from the pull-rod, whereby the register 75 is operated once for every two opposite movements of said lever, as shown and described.

WILLIAM B. THOMAS.
